UNITED STATES PATENT OFFICE.

WILLIAM BLAU, OF NEW YORK, N. Y.

FUR-CUTTING IMPLEMENT.

1,310,736.

Specification of Letters Patent. Patented July 22, 1919.

Application filed September 7, 1918. Serial No. 253,092.

To all whom it may concern:

Be it known that I, WILLIAM BLAU, a citizen of the United States, and a resident of the city of New York, in the county 5 of New York and State of New York, have invented certain new and useful Improvements in Fur-Cutting Implements, of which the following is a specification.

The present invention relates to an implement used in serrating or zigzagging the edges of fur pieces. When fur pieces are to be stitched together, the meeting edges of the two pieces are serrated or zigzagged, if the cut runs transversely of the 10 fur. This serrating or zigzagging is performed in order to produce a joint between the two pieces that is invisible on that side of the skin on which the fur fibers are disposed.

20 The zigzagging or serrating operation is performed usually by a knife or cutter, care being taken that the skin is snipped without injuring or severing the fur fibers, covering the same. A pattern is usually used, by 25 means of which a zigzag line is drawn on the skin, to be followed then by the cutting knife.

The main object of the present invention is to provide an implement which greatly 30 simplifies the snipping operation, in that it clamps the edge of the fur to be serrated or zigzagged, serving at the same time as a guide along which the knife is drawn to perform the cutting operation.

35 Another object of the invention is to provide an implement of this type, which is simple in construction, efficient in operation and which can be manufactured on a commercial scale, or in other words, one 40 which is not so difficult to produce as to be beyond the reasonable cost of such an article.

With these and other objects in view which will more fully appear as the nature 45 of the invention is better understood, the same consists in the combination, arrangement, and construction of parts hereinafter described, pointed out in the appended claims and illustrated in the accompanying drawings, it being understood that many 50 changes may be made in the size and proportion of the several parts and details of construction within the scope of the appended claims without departing from the spirit or sacrificing any of the advantages of the 55 invention.

Two of the many possible embodiments of the invention are illustrated in the accompanying drawings, in which:

Figure 1 is a top plan view of an implement constructed in accordance with the present invention, part of one of these elements being broken away, to more clearly show the interior construction; Fig. 2 is a section taken on line 2—2 of Fig. 1; and Fig. 3 is a top plan view of a modification of the invention.

Referring now first to Figs. 1 and 2 of the drawings, the numeral 10 indicates a base plate, provided with a sinuous front edge 11, and with an upwardly extending ledge 12 along its rear longitudinal edge. To this ledge is hinged at 13 a clamping plate 14, the front edge 15 of which is preferably beveled, its contour corresponding to that of the front edge 11 of the base plate 10, that is to say it is also sinuous. The two wavy front edges of the base plate and clamping plate are in alinement, as clearly appears from Fig. 1 of the drawings. Upon the base plate are mounted upwardly extending pins 16, which are disposed preferably, equidistantly along the sinuous front edge of the said base plate, their upper ends being substantially flush with the upper surface 17 of the ledge 12. Two larger pins 18 are attached to the base plate near its ends and as close as possible to the front edge thereof, said pins being adapted to project through apertures 19 in the clamping plate, when the latter is in its clamping position.

To the clamping plate is pivoted at 20 a bar 21, that extends through a slot 22 in the base plate, and has pivoted to its lower end a treadle 23. The bar 21 extends also through a slot 24 in a support 25, upon which the implement is placed. A spring 26 is attached at one of its ends to the support 25 and at its other end to a projection 27 upon the bar 21, said spring having a tendency to hold the clamping plate 14 in its raised position shown in dotted lines in Fig. 2 of the drawings.

The operation of the device is as follows:—The edge of the fur to be cut is placed, with the fur fibers face down, onto the pins 16, care being taken that the edge to be cut does not extend at a greater distance in front of the said pins than is necessary, in order to prevent wasting of material.

The pins 18 are passed through the fur in order to hold the same in stretched position. The plate 14 is then brought into clamping position by moving the treadle in the direction of the arrow shown in Fig. 2 of the drawings, whereby the work is held in proper position upon the implement. Attention is called to the fact that the edge of the work to be cut is supported by the pins 16 only. The fur fibers are thus permitted to extend vertically downward, and due to this fact the knife, in performing the cutting operation, cuts the skin of the fur only, but leaves the fur fibers intact. After the clamping plate has been brought into its operative position, the operator cuts the fur by drawing a knife along the sinuous edge of the clamping plate. The clamping plate has thus a two-fold function, to wit: First, it serves as the means for holding the fur in place, and second, it constitutes a pattern for the cut to be made. After the cutting operation, the operator lets go of the treadle, whereby the spring 26 shifts the clamping plate 14 to its inoperative position, thereby permitting the fur to be removed from the base plate.

The modification shown in Fig. 3 of the drawings differs from the one above described, in that the front edges of the base and clamping plates are zigzagged, instead of sinuous. By means of this implement the edge of the fur is provided with a zigzag edge.

It is to be noted that both the zigzag and sinuous lines, in which the pins 16 of the implement are disposed, are composed of a plurality of regular and alternate turns.

What I claim is:—

1. In an implement of the character described, the combination with a base plate having a serrated front edge composed of a plurality of regular and alternate turns, a clamping plate hinged to said base plate provided with a free edge having a contour corresponding to that of the front edge of said base plate, the serrations in both plates

being continuous, a line of upwardly extending pins attached to said base plate in rear of and in parallel relation to the front edge of said base plate, the free edge of said clamping plate being adapted to rest on the fur on said pins and being then in alinement with the front edge of said base plate, and means for moving said clamping plate into clamping position.

2. In an implement of the character described, the combination with a base plate having a serrated front edge composed of a plurality of regular and alternate turns, a clamping plate hinged to said base plate provided with a free edge having a contour corresponding to that of the front edge of said base plate, the serrations in both plates being continuous, and a line of upwardly extending pins attached to said base plate in rear of and in parallel relation to the front edge of said base plate, the free edge of said clamping plate being adapted to rest on the fur on said pins and being then in alinement with the front edge of said base plate.

3. In an implement of the character described, the combination with a base plate having a serrated front edge composed of a plurality of regular and alternate turns, of an upwardly extending ledge along the rear edge of said plate, a clamping plate hinged to said ledge provided with a free edge having a contour corresponding to that of the front edge of said base plate, a line of upwardly extending pins attached to said base plate in rear of and in parallel relation to the front edge of said base plate, the points of said pins being disposed in the plane of the upper face of said ledge so that the free edge of said clamping plate is adapted to rest on the fur on said pins and is then in alinement with said front edge of said base plate.

Signed at New York, in the county of New York, and State of New York, this 2nd day of August, A. D. 1918.

WILLIAM BLAU.
